UNITED STATES PATENT OFFICE.

FRANK L. O'DONNELL, OF CHICAGO, ILLINOIS, ASSIGNOR TO KIRSCH COMPANY, OF STURGIS, MICHIGAN, A CORPORATION OF MICHIGAN.

DESIGN FOR AN END ORNAMENT FOR A DRAPERY-SUSPENSION FIXTURE.

Application filed December 22, 1928. Serial No. 29,380. Term of patent 3½ years.

To all whom it may concern:

Be it known that I, **FRANK L. O'DONNELL**, a citizen of the United States, and a resident of Chicago, county of Cook, and State of Illinois, have invented a new, original, and ornamental Design for an End Ornament for a Drapery-Suspension Fixture, of which the following is a specification, reference being had to the accompanying drawing, forming a part hereof, which is a front perspective

view of a drapery fixture showing a curtain pole and supporting brackets therefor in dotted lines and the end ornaments for a drapery suspension fixture in full lines, the latter showing my new design.

I claim:

The ornamental design for an end ornament for a drapery suspension fixture as shown and described.

FRANK L. O'DONNELL.
